PLANTER

Louis Charpentier, Leominster, Mass., assignor to Gilbert Josephson, White Plains, N.Y.

Filed Oct. 20, 1960, Ser. No. 62,550

Term of patent 14 years

(Cl. D35—3)

FIG. 1

FIG. 1 is a front perspective view taken from the right side of a planter showing my new design; and

FIG. 2 is a left side elevational view thereof.

The rear of the planter's back and the inside of both arms are substantially smooth, the apron beneath the front of the seat is repeated at the rear of the seat, and the rear legs are essentially the same as the front legs.

I claim:

The ornamental design for a planter, substantially as shown and described.
